WINDOW FASTENER

Filed April 22, 1926

UNITED STATES PATENT OFFICE.

RAYMOND BORDEN, OF XENIA, OHIO, ASSIGNOR OF ONE-HALF TO CHARLES H. TATE,
OF RICHMOND, INDIANA.

WINDOW FASTENER.

Application filed April 22, 1926. Serial No. 103,987.

The object of my present invention, broadly stated, is the provision of a new and novel arrangement which may be installed in connection with ordinary windows whereby the window may be partly closed or fully closed by a person located at a distance therefrom, the construction of the operating means being simple in character, positive in operation, easy of installation and operation, and which can be manufactured and sold at a comparatively low price.

One manner of carrying out the principles of this invention in a practical, efficient, and economical manner, is shown in the accompanying drawings, in which—Figure 1 is an elevation of a portion of a window frame, looking toward the edges of the sashes, which are closed. Figure 2 is an elevation of a portion of a window, taken at right-angles to Fig. 1 partly in section taken on line 2—2 of Fig. 1, showing the mechanisms for the two sashes and also indicating the sashes as closed. Figure 3 shows a portion of a window, taken at right-angles to Fig. 1, but showing the sashes as opened. Figure 4 is a face view of one of the enclosing plates, and showing parts of the mechanism through apertures therein, Figure 5 is a face view of one of the racks. And Figure 6 is a diagram of the wiring, in connection with certain of the parts.

Similar indices denote like parts throughout the several views.

In order that the construction, the operation, and the several advantages of my invention may be more fully understood and appreciated I will now take up a detailed description thereof, in which I set forth the same as comprehensively as I may.

In the drawings numeral 1 denotes a portion of one side of a window frame.

Slidably mounted to move up and down in the frame 1 are the usual sashes 2 and 3, each surrounding and carrying a transparency, 4 and 5, respectively.

In the upper portion of each side of the frame 1 apertures are formed in which are mounted the usual channeled pulleys 6 and 7, over which operate the respective sash cords 8 and 9, one end of each being secured to the upper portion of the respective sashes 2 and 3, in the usual manner, and their other ends are secured to their respective weights 10 and

11. It, of course, is to be understood that the other side of the frame (not shown) and 55 sashes are likewise equipped with pulleys, cords, and weights, identical with that shown. Said weights are such as to normally close said sash to their limits of movement, raising or lowering them automatically when 60 released.

All of said parts are of ordinary construction and I make no claim thereto, neither am I to be limited to the same.

Located at any convenient place, for instance in the upper part of the frame 1 as shown, is a transformer 12, from one end of which extends the usual double wiring 13, which is of any suitable length such as to extend to a socket connected with the usual 70 electric wiring of the building. Said double wire is connected into a screw-plug 14 which is adapted to be inserted in said socket whereby electric current may be provided to operate my devices.

The remainder of the construction, that is the trigger devices, are in duplicate, one for each of the sashes, therefore a description of one will answer for both, however I will now describe the upper one of said devices, and 80 the members of the other will be denoted by like reference characters.

Formed through the side of the frame are the oblong apertures A, one in alignment with the edge of each sash, each is covered by a 85 plate 15, which is let in flush with the inner face of the side of the frame 1, to which it is secured by screws 16, which are inserted through the apertures 17 of the plate. Formed through the central part of the plate 90 15 is a square aperture 18, the material by which it is formed being turned back at right-angles to form ears 19. A bolt 20 is disposed across through said ears to form a pivot for, and at the lower end of, the trigger 21. Also 95 formed through the plate 15, near one end thereof, is an aperture 22.

One end of the trigger 21 is turned inward at right-angles forming a tooth 23 which extends through the aperture 22, and normally would slide in contact with the edge of the sash. The other end portion of the trigger 21 is turned outward, opposite of the tooth 23, and at right-angles to the body of the trigger 21 and forms an armature 24, for the 105 purpose hereinafter set forth.

Secured to the outer face of the plate 15 is a bracket 25, which carries an induction coil 26, the latter having its core 27 exposed at one end where it is near the armature 24, which is adapted to contact therewith.

Secured in the edge of each sash is a rack 28 with which the teeth 23 are adapted to engage. Said racks are formed with notches having horizontal faces forming shoulders, and angular faces connecting said horizontal faces, substantially as shown in the drawings.

Connected around the projecting end portions of the bolt 20, with its ends secured thereby, is a coil spring 29 whose central portion forms a loop which contacts with the trigger 21 and retains its resiliency in contact with the back of the plate 15, with the tooth 23 projecting through the aperture 22, as in Figs. 2 and 3.

For the upper sash said device, including the plate 15 and the parts connected thereto, and the rack 28, is arranged as shown in the upper portion of Figs. 1, 2 and 3, while for the lower sash said parts are reversed, that is they are arranged as shown in the lower portions of Figs. 1, 2 and 3, that is they are turned end-for-end.

It will now be apparent that if the upper sash be lowered, from its closed position in Figs. 1 and 2, that the tooth 23 will be pressed outward by the angular faces of the rack 28 and, by reason of the spring 29, will be caused to engage one of the shoulders of the rack, as in Fig. 3, thereby preventing the sash from being closed by the weights. The lower sash will operate in the same manner except that the movements will be reversed from that stated.

In order to release the tooth 23 from the shoulders of the rack electric means are provided in connection with the transformer, which means I will now describe in detail.

Numeral 30 denotes a push button for the control of the upper sash, and 31 denotes the push-button for controlling the lower sash. Said buttons may be on the same plate, or connected with the same switch, or they may be spaced some distance apart as desired.

The transformer has two terminals, 32 and 33. Extending from the terminal 32 is a wire 34, which is connected directly with one pole of the upper coil 26. Also extending from terminal 32 is a wire 35 which connects directly with a like pole of the lower coil 26.

Extending from the terminal 33 is a wire 36 which connects with one pole of the switch 30, and extending from the terminal 33 is a wire 37 which connects with one pole of the switch 31.

Extending from the other pole of the switch 30 is a wire 38, which connects with the other pole of the coil 26, and likewise extending from the other pole of the switch 31 is a wire 39, which is connected with the other pole of the lower coil 26.

If, now, the screw plug 14 be connected with the usual lighting system of a building, the switches 30 and 31 normally being open, it is evident that no current will flow through the system. However should the switch 30 be then closed the current will flow through the upper coil, magnetizing the upper core 27, which will attract its armature 24 thereto, thereby slightly turning the upper trigger 21 and causing the tooth 23 to move out of engagement with its rack 28 and therefore leaving the upper sash free to be raised by its weights. In like manner by closing the switch 31 the lower sash will be lowered and closed in the same way.

The transformer 12 should be of the proper capacity to change the usual current of the light system into current that is suitable for magnetizing the coils 26 to the proper degree.

Now when the switch 30 is closed it will be seen that a circuit will be established from one pole of the transformer, that is from the terminal 32, through the wire 34, the upper coil 26, the wire 38, the switch 30, the wire 36, and then to the terminal 33 of the transformer 12, thereby completing the first circuit.

In like manner when the switch 31 is closed a circuit will be established from the terminal 32, through the wire 35, the lower coil 26, the wire 39, the switch 31, and the wire 37, to the terminal 33 of the transformer 12, thereby completing the second circuit. By the above arrangement it is evident that each circuit is complete per se, yet both drawing current from the same source of power.

In practice the weights 10 for the sash 2 should be of greater weight than the sash 2, in order that the sash 2 will move upward automatically to closed position when it is released. Also the weights 11 for the lower sash 3 should be of less weight than is the sash 3, in order that the sash 3 will move downward automatically to closed position when it is released.

By reason of the plurality of shoulders formed by the rack 28 it is evident that the sashes may be opened and suspended at various degrees of elevation, and then they may be closed from any point where they are left by simply pressing the button of the switch 30 or 31, that is to say by closing one or both of said switches. By quickly closing and opening one of the switches it is evident that the sash may be allowed to move a step at a time, moving the tooth 23 from one to another of the shoulders of the rack, thereby enabling one to only partly close the sashes if desired.

It is to be understood that various changes may be made in the details herein set forth without departing from the spirit of my invention or sacrificing any of the advantages thereof.

Having now fully shown and described my invention, what I claim and desire to secure by Letters Patent, is—

In combination with a window-frame having an upper and a lower sash slidable up and down therein, a mechanism for each sash secured in apertures in said frame and each comprising a plate secured over an aperture in said frame and a square aperture formed 10 through said plate, ears extending out from the sides of said square aperture, a pivot-bolt extending across through said ears, a trigger pivoted at its lower end to said bolt, a tooth forming the inner terminal of the 15 trigger and which extends through a second

aperture in said plate and normally in contact with the edge of its sash, an armature formed by the outer portion of said trigger, an induction coil carried by said plate with its core located near said armature, a spring 20 attached to said bolt and to the trigger to normally retain the trigger in contact with said plate with said tooth projecting through said second aperture in the plate, and means whereby said induction coil may be magnetized and demagnetized by a person located at a distance therefrom, all substantially as shown and described and for the purposes set forth. 25

RAYMOND BORDEN.
